R. H. HUGHEY,
ATTACHMENT FOR SPINDLE BEARINGS,
APPLICATION FILED MAY 4, 1921.

1,424,646.

Patented Aug. 1, 1922.

UNITED STATES PATENT OFFICE.

ROBERT H. HUGHEY, OF GREENWOOD, SOUTH CAROLINA.

ATTACHMENT FOR SPINDLE BEARINGS.

1,424,646.

Specification of Letters Patent. Patented Aug. 1, 1922.

Application filed May 4, 1921. Serial No. 466,676.

To all whom it may concern:

Be it known that ROBERT H. HUGHEY, a citizen of the United States, and a resident of Greenwood, in the county of Greenwood and State of South Carolina, has invented certain new and useful Improvements in Attachments for Spindle Bearings, of which the following is a specification.

This invention relates to an attachment for spindle bearings; the bearings being of the type employed for rotatably supporting one end of a bobbin spindle, such as used in spinning frames or machinery. Briefly, the construction of the conventional form of bearing of the type above referred to consists of a short post, a portion of which is provided with a longitudinal bore adapted for receiving a bobbin spindle, the end of the spindle being suitably seated in the lower end of the bore. The bearing and spindle are positioned vertically and suitably secured in a base. The bobbin is suitably carried upon the upper end of the spindle and between the bobbin and bearing there is formed on the spindle a V-groove pulley about which there extends a belt for driving the spindle. The spindle is rotated at a high rate of speed and its journaled portion is continuously immersed in suitable lubricating oil through an oil reservoir which is formed on the upper end of the post bearing. The reservoir is substantially U-shaped in formation, one terminal terminating with the bearing and the other terminating in close proximity to the upper side of the V-groove pulley. An oil opening is provided for the upper end of the reservoir and a cap adapted for forming a closure for said opening. The cap is so formed and mounted that when it is lowered its one end projects sufficiently to limit the upward movement of the spindle by engaging the pulley carried by said spindle; also when the cap is lifted or raised the pulley is permitted to pass and the spindle freely removed from its bearing.

In practice, it has been found that the bobbin has a tendency to rise from the spindle, and in order to overcome this the bobbin is usually driven down so that it may better grip the spindle. This makes the bobbin difficult to remove and often the oil caps of the reservoir heretofore referred to are broken during the removal of the bobbin. After the cap has been broken there is nothing to hold the belt from rising upon the bobbin and doing considerable damage, nor

to prevent the spindle from being jerked out of its bearings.

With that heretofore recited in mind it is the object of the present invention to provide an attachment by which broken bearings may be quickly and easily repaired and when so repaired will serve to prevent the belt from rising on the bobbin of yarn.

It is also an object of the invention that the attachment be adapted to be applied to unbroken bearings and serve as a preventative of the possible breakage or destruction heretofore mentioned.

Other objects will hereinafter appear.

The invention is illustrated by way of example in the accompanying drawings, in which:

Figure 1 is a front elevation of a bearing and spindle together with the bobbin carried thereby and also showing my invention when applied.

Figure 2 is a transverse section on the line 2—2 of Figure 1.

Figure 3 is a top plan view of the attachment as when applied to the oil reservoir and associated parts being shown in dotted lines.

Referring to the drawings more particularly, 10 indicates a post bearing at the one end of which there is suitably journaled the bobbin spindle 11 and said bobbin spindle being properly seated upon its lower end in the usual manner. The upper end of the spindle has secured thereto a sleeve 12, upon the lower end of which there is formed a V-grooved pulley 13 adapted to accommodate a rope belt 13', and upon the upper end of said sleeve there is suitably mounted and secured a bobbin 14.

On the upper end of the post bearing 10 there is formed a flange 15 which is tapered into a hub like portion 16 at its upper side; also the post bearing 10 is provided with the threads 17 which accommodate a nut 18. The nut 18 and flange 15 serving to clamp the post bearing to a suitable base as indicated at 19. The flange 15 and its extended hub portion 16 has formed therewith a reservoir 21 which consists of a hollow U-shaped member, the upper end of which is provided with an oil opening 22, Figure 2, and also provided upon said end is a cap 23 being adapted to cover said opening and pivotally mounted for upward and downward swinging movement. The cap 23 has a portion 24 which extends from the upper terminal of the reservoir 20 sufficiently to engage the

one side of the pulley 13, in case said pulley rises and in this manner limits the upward movement of the shaft 11.

To the structure heretofore recited I make 5 no claim.

My invention consists in an attachment 10 for the reservoir 20 and consists of a device as shown in full lines in Figure 3. Referring more particularly to Figure 3, 25 10 indicates a U-shaped clip, the terminals of which are formed with suitable openings 26 which are adapted to receive the screw bolt 27 by which the member may be clamped about the reservoir 20 of the bearing post 15 10 as shown in Figures 1 and 2. Upon one edge of the bridge portion of this U-shaped clip there is formed a plate like finger 28 which is slightly curved inwardly at its outer end as at 29; also there is formed with 20 the plate-like member 27 an outwardly curved portion 30 which has an offset 31 in its outer end as shown.

The attachment is positioned as shown in 25 Figures 1 and 2 and the outer end of the finger 28 extends in close proximity to the one side of the pulley 13 and forms a substantial stop for said pulley and thus restricting the upward movement of the spindle 11. The offset 30 permits the upward 30 and downward swinging movement of the outer portion 24 of the cap 23, in case the attachment is applied to an unbroken reservoir or bearing.

I claim:—

- 35 1. In an attachment for a spinning spindle of the character described, comprising a U-shaped clip having a finger extending from the bridge portion thereof, and means for connecting the ends of said clip.
- 40 2. An attachment for spinning spindles of the character described, comprising a U-shaped clip, a screw bolt for connecting the leg terminals of said clip, and a plate like finger formed upon the one edge of the bridge portion of said clip and extending at substantially right angles to the legs of the clip.
- 45 3. In an attachment for spinning spindles of the character described, comprising a U-

shaped clip, a screw bolt for connecting the 50 leg terminals of said clip, and a plate like finger formed upon the one edge of the bridge portion of said clip, said finger extending at substantially right angles to the leg portions of said clip and having its inner 55 ends slightly curved inwardly.

4. In combination, a rotatable spindle, a pulley carried thereby about which passes a belt adapted for driving the spindle, a stationary support in close proximity to the 60 spindle, and an attachment adapted to be secured to the support and to prevent movement of the spindle in one direction.

5. In combination, a vertical spindle, a post bearing for rotatably supporting the 65 lower end of said spindle, said post bearing having an extension formed therewith serving as an oil reservoir and said extension being in close proximity to the spindle, a pulley carried by the spindle and positioned adjacent the post bearing and about which a belt passes for rotating the spindle, and an attachment adapted to be secured to the extension of the post bearing and to serve for preventing upward movement of the spindle. 70

6. In combination, a rotatable spindle, a post bearing for rotatably supporting the lower end of said spindle, said post bearing having an extension formed therewith serving as an oil reservoir and said extension being in close proximity to the spindle, a pulley carried by the spindle and positioned adjacent the post bearing and about which a belt passes for rotating the spindle, an attachment adapted to be secured to the extension of the post bearing and to serve for preventing upward movement of the spindle, said attachment consisting in a U-shaped clip, the leg portions of which are adapted to straddle the oil reservoir extension of the post bearing, means for clamping the legs about the oil reservoir extension, and a finger extending from the bridge portion of said clip adapted to be disposed in close proximity to the upper side of the 95 pulley.

ROBERT H. HUGHEY.
